UNITED STATES PATENT OFFICE.

FRANK R. WOOD AND DANIEL FREDERICK SHAMBERGER, OF SPARROWS POINT, MARYLAND.

AUTOMATIC TRAIN SIGNALING AND RECORDING SYSTEM.

SPECIFICATION forming part of Letters Patent No. 763,939, dated June 28, 1904.

Application filed August 24, 1903. Serial No. 170,598. (No model.)

To all whom it may concern:

Be it known that we, FRANK R. WOOD and DANIEL FREDERICK SHAMBERGER, residing at Sparrows Point, county of Baltimore, and State of Maryland, have invented certain new and useful Improvements in Automatic Train Signaling and Recording Systems, of which the following is a specification.

Our present invention relates to improvement in railroad-train-signaling systems, and it more particularly seeks to provide an improvement upon the signaling system disclosed in our copending application filed on even date herewith and bearing the Serial No. 170,597; and the invention primarily consists of a series of main-line wires including a number of signaling mechanisms arranged at predetermined distances along the railroad-line, together with a plurality of time-stamp and recording devices, one for each main-line wire, all of which time-stamp and recording devices being preferably located at the main or central station.

Another object of our invention is to provide means for cutting out the remaining stations along the railroad-line when one transmitter or signal-station has sent in its signal and to set a suitable signal at each succeeding station cut out to show that the said station has been cut out to connection with the main or central station to prevent trains passing by said station without sending in their respective signals.

With other objects in view, which will hereinafter be made apparent, the invention consists in the novel construction and combination of parts, which will be first described in detail and then specifically pointed out in the appended claims, reference being had to the accompanying drawings, in which—

Figure 1 is a diagrammatic view of our invention. Fig. 2 is a top plan view of the transmitter-box, the cover being removed. Fig. 3 is a longitudinal section thereof, taken practically on the line 3 3 of Fig. 2. Fig. 4 is a detail view of the cut-out or commutator mechanism. Fig. 5 is a detail view of one of the commutator-disks and its line connections.

Referring now to the accompanying draw-

ings, in which like numerals and letters of reference indicate like parts in all the figures, 1, 2, 3, 4, 5, and 6 designate the main-line wires having the common ground connection g at their ends, and the said wires each include time-stamp devices T and recording mechanisms R, located at a central station C.

Arranged at suitable intervals along the railroad-line are a number of signaling or transmitting mechanisms, (designated generally by M,) which are shown in detail in Figs. 2 to 5, inclusive, by reference to which it will be seen we provide a rotary shaft 15, and secured to rotate therewith are a series of commutator-disks 16, one for each main-line wire and each being of like construction, and the said shaft 15 also carries a signaling-wheel 17, having a series of signaling-teeth corresponding in number and arrangement to the number of commutator-disks for a purpose presently to appear.

Secured to rotate with the shaft 15 is a ratchet 18, having a number of teeth 18^a equal to the number of commutator-disks and with which the pawl 19, pivotally mounted at 19^a to the casing m, engages.

20 designates a rod or bar mounted from vertical movement on the stud 20^a and connected at its lower end with the pawl 19, while at its upper end the bar 20 has a finger 20^b, spring-held to its normal position at right angles to the bar 20 by a spring 20^c, as shown in Fig. 3, and with which the end 21^a of the rocking lever 21, pivoted at 21^b to the casing m, engages, and the said lever 21 has a pendant armature-carrying rod 22, having an armature 22^a for coöperating with the releasing-magnet 23, connected by wires 23^b to the track-rails t t and the battery B. The said lever 21 is held to its normal position by a spring 21^c, as shown.

15^b designates a pinion carried by the shaft 15, which meshes with a gear 15^c in the counter-shaft 15^d, also having a pinion 15^e meshing with the gear-surface 25^a of the drive-motor casing 25, mounted to rotate on its shaft 26, to which and to the casing 25 the coil-spring 25^b, carried within said casing 25, is connected, and the said shaft 26 is held

from normal rotating by the ratchet-and-pawl connection 26^y 26^z, as shown. The shaft 26 also carries a winding-key 26^m, whereby to wind up the motor-spring when run down.

5 By referring now more particularly to Figs. 2 and 5 of the drawings it will be seen that each commutator-disk 16 includes a portion 16^o of fiber or other insulating material, to the circumference of which is attached a split 10 metallic ring 16^b, extending about five-sixths the circumferential length of the disks 16^a, so as to leave an insulating portion 16^c equal in length to one-sixth of the circumferential distance of the disks 16. In a countersunk portion 15 of one side of the insulating portion 16^c is a metallic strip 16^d, having a portion 16^e in electric contact with the shaft 15, and the disk 16 is held on the shaft 15 by collars 15^x, one of which is held in tight electrical engagement 20 with the portion 16^c and the shaft 15 to conduct the current from the strip 16^d to the shaft and from thence to the metallic signaling-wheel 17, having signaling-teeth 17^y through the brush 17^a to the ground.

25 27 28 indicate a pair of contact-brushes adapted to engage with the commutator-disk 16 and which are connected in series with the main-line wires. The said brushes 27 28 engage the side faces of the split metallic ring 16^b 30 during five-sixths of a revolution of the commutator-disk 16, while during the remaining one-sixth revolution the metallic or electrical connection is broken by the engagement of one of the brushes with the insulating portion 35 16^c. Any suitable signaling mechanism, such as lamps L, may be connected to the main-line wires to show that the said line-wires are cut out or dead, the system being a normally closed circuit one operated by the main battery B.

40 From practical experience we have found that the resistance between the rails of a railroad having a stone bed as now generally constructed is sufficient to avoid the necessity 45 of insulating the rails to which the terminals from the magnet 23 connect. However, whenever it may be necessary we may insulate the rails.

So far as described the manner in which our 50 invention operates can be best explained as follows: Assuming the trains to be passing from left to right in Fig. 1, as the first train arrives at the transmitter-station A it will bridge the track-rails to operate the magnet 55 23, which will pull down its armature and cause the rocking lever to lift the vertical movable bar to momentarily release the pawl 19 from the ratchet 18, which will permit the commutator-disks to revolve until the brushes 60 27 28 of the first commutator-disk leave the metallic rim and the brush 28 comes in contact with the strip 16^d, while the other brush, 27, engages the insulation at the other side of the strip. This cuts out the remaining portion 65 of the line and grounds the portion between

the station A and the central station through shaft 15 and signal-wheel 17, which wheel at the same time, by reason of its signaling-teeth, sends in the station-signal to the time-stamp and recording mechanism through the line-wire 1. The remaining commutator-disks continue to have their brushes in contact with their respective rings 16^b, so as not to cut out the remaining line-circuits. As the first train leaves the vicinity of the station A the magnet 23 will release its armature, allowing the rocking lever to again engage the finger on the vertically-movable bar 20. It should be understood the shaft 15 only revolves one-sixth of a revolution for each operation of the 80 magnet 23. The strip 16^d is so arranged that the brushes will pass onto the ring 16^b just prior to the time the rotation of the shaft 15 is stopped. As the second train arrives at station A the same cycle of operations takes 85 place, the main line portion 2^a being grounded through its commutator-disks 16 and the signal-wheel 17, while the rest of the line 2 is cut out, the signal being recorded on its respective recording and time-stamp mechanism. The operation is the same for each successive train. The first train operates its recording and time-stamp mechanism through the main-line wire 1, the second train through the main-line wire 2, and so on. As the first 90 train arrives at the second station A' the same operation takes place in its signaling or transmitting mechanism as for station A. Should the sixth train to pass station A be about to enter the limits of station A' at the same time 95 the seventh train is sending in the signal through the line-wire 1 at station A, the signaling-light L (or other device) at station A' will be out, showing the engineer of the sixth train that his portion of the line is cut out at 100 station A'. As soon as the signal is completed at station A (almost instantaneously) the line at station A' will be again cut in and the signal-lights at station A' again set to show "Clear." The sixth train may then pass said 105 station A' and operate its signal.

From the foregoing description, taken in connection with the accompanying drawings, it is thought the advantages and complete operation of our invention will be readily apparent to those skilled in the art to which it 110 pertains.

Having thus described our invention, what we claim, and desire to secure by Letters Patent, is—

1. In a train signaling and recording mechanism, a plurality of main-line circuits including recording devices, of a transmitter mechanism common to all of said main-line circuits, said transmitter mechanism adapted to cut out 115 a portion of the main-line circuits at predetermined times, for the purposes specified.

2. In a train signaling and recording mechanism, a plurality of main-line circuits including recording devices, a transmitter mechan- 120

ism common to all of said main-line circuits, said transmitter mechanism adapted to be set in operation by the passing train, to cut out a portion of the main-line circuits and send in 5 a signal to the recording mechanism through the remaining portion of the circuit, as specified.

3. A plurality of main-line circuits, transmitter mechanism common to all of said circuits 10 and including means for grounding a portion of one of the said main-line circuits and cut out the remaining portion thereof, whereby to permit sending in a signal through said grounded portion and prevent signaling 15 through said cut-out portion of the main-line circuit, as specified.

4. In a train signaling and recording system, including a plurality of main-line circuits each including recording mechanisms, of a 20 transmitter device, said device including a plurality of commutator-disks one for each main-line circuit, and a signal-wheel in electric contact with said disks, and with the ground, said line-circuits having grounded terminals, said 25 commutator-disks adapted to ground a portion of one of said main-line circuits through the signal-wheel, and to cut out the other portion of said circuit, at predetermined times, for the purposes specified.

30 5. In a train signaling and recording system, including a plurality of main-line circuits each including recording devices, of a transmitter mechanism, said mechanism including a plurality of commutator-disks, one for each 35 main-line circuit, and a signal-wheel in electric contact with said disks and with the ground, said main-line circuit having grounded terminals, means for releasing said transmitter mechanism so that said commutator-disks will ground a portion of one of said main-line 40 circuits through the signaling-wheel, and cut out the other portion of said circuit at predetermined times.

6. In a signaling system, a plurality of independent main-line circuits each including recording devices, of a transmitter mechanism common to all of said main-line circuits, said transmitter mechanism being controlled by the passing train and adapted to successively 45 connect each of the main-line circuit portions between the recording mechanism and the transmitter mechanism to the ground at predetermined times, and to simultaneously cut out the remaining portion of the said grounded 55 circuit, for the purposes specified.

7. In a signaling system, a plurality of independent main-line circuits each including recording devices, of a transmitter mechanism common to all of said main-line circuits, said 60 transmitter mechanism being controlled by the passing train and adapted to successively connect each of the main-line circuit portions between the recording mechanism and the transmitter mechanism to the ground at predetermined times, and to simultaneously cut

out the remaining portion of the said ground-circuit, and a signaling-wheel in said ground connection adapted to send a signal through the so grounded portion of the particular main-line circuit to operate its respective recording mechanism, for the purposes specified. 70

8. In a train signaling and recording system including a plurality of main-line circuits including recording mechanisms, a series of transmitter mechanisms common to all of said 75 main-line circuits, and arranged at suitable intervals apart, a drive-motor for each of said transmitter mechanisms, means for controlling said mechanisms by the passing train, each of said transmitter mechanisms being adapted to 80 send a signal to the recording mechanism of one circuit and cut out the succeeding transmitter mechanism in that circuit at predetermined times.

9. In a transmitter mechanism for electric 85 signaling systems including a plurality of main-line circuits having recording devices, a plurality of commutator devices one for each main-line circuit, each of said commutator devices including grounded segments, main-line 90 contact-terminals for coöperating with the commutator devices, said commutator devices being so arranged as to ground a portion of one main-line circuit and cut out the other portion thereof, for the purposes specified. 95

10. In a transmitter mechanism for electric signaling systems including a plurality of main-line circuits having recording devices, a plurality of commutator devices one for each main-line circuit mounted to move in unison 100 each of said commutator devices including grounded segments all of said grounded segments having a common ground connection, a signal-wheel included in said ground connection, said commutator devices being so arranged as to ground a portion of one main-line circuit and simultaneously cut out the other portion thereof, for the purposes specified. 105

11. In a transmitter mechanism for electric 110 signaling systems including a plurality of main-line circuits having recording devices therein, a plurality of commutator devices one for each main-line circuit mounted to move in unison, each of said commutator devices including grounding segments, all of said grounding segments having a common ground connection, a signal-wheel included in 115 said ground connection and adapted to move in unison with said commutator devices, main-line contact-terminals for coöperating with the commutator devices, said commutator devices being so arranged as to ground a portion of one main-line circuit and simultaneously cut out the other portion thereof, for the purposes specified. 120

12. In a train signaling and recording system, a plurality of main-line wires including independently-operated recording devices, a series of transmitter mechanisms common to 125

130

all of said main-line circuits adapted to be set in operation by the passing train, said transmitter devices including commutator mechanisms for cutting out a portion of the main-line circuit at predetermined times, signaling devices included in such cut-out portion of the main-line circuits, for the purposes specified.

13. In a transmitter mechanism for electric
10 signaling systems, a plurality of main-line wires and recording mechanisms therefor, of a plurality of commutator devices, each in-

cluding grounded segments, main-line contact-terminals for coöperating with the commutator devices, said commutator devices being so arranged as to ground a portion of one circuit and cut out the other portion thereof, for the purposes described. 15
